DESIGN FOR A PIANO

Adolf Klein, New York, N. Y.

Application July 17, 1935, Serial No. 57,704

Term of patent 3½ years

To all whom it may concern:

Be it known that I, Adolf Klein, a citizen of the United States and a resident of the city of New York, Borough of Bronx, county of Bronx, and State of New York, have invented the new, original, and ornamental Design for a Piano, shown in the accompanying drawing, in which the figure is a perspective view of the piano showing my design.

I claim:

The ornamental design for a piano as shown.

ADOLF KLEIN.
